R. S. TYLER.
PAPER CUTTING MACHINE.
APPLICATION FILED APR. 8, 1919.

1,413,206.

Patented Apr. 18, 1922.

UNITED STATES PATENT OFFICE.

RALPH S. TYLER, OF CLEVELAND HEIGHTS, OHIO, ASSIGNOR TO THE CHANDLER AND PRICE COMPANY, OF CLEVELAND, OHIO, A CORPORATION OF OHIO.

PAPER-CUTTING MACHINE.

1,413,206.

Specification of Letters Patent. Patented Apr. 18, 1922.

Application filed April 8, 1919. Serial No. 288,556.

To all whom it may concern:

Be it known that I, RALPH S. TYLER, a citizen of the United States, and a resident of Cleveland Heights Village, county of

5 Cuyahoga, and State of Ohio, have invented a new and useful Improvement in Paper-Cutting Machines, of which the following is a specification, the principle of the invention being herein explained and the best 10 mode in which I have contemplated applying that principle, so as to distinguish it from other inventions.

In machines of the class in hand, it has been found desirable, for obvious reasons, to 15 impart a transverse as well as a vertically reciprocable movement to the knife which trims the stock, so as to impart a so-called "shear stroke" to such knife. This is ordinarily accomplished by providing an inclined guideway in the frame in which the knife is thus vertically reciprocable, and attaching to the knife or its carrier a slide movable in said guideway, so that as the knife is depressed, as in the cutting operation, 20 it is simultaneously shifted longitudinally. In a machine thus constructed, however, where the vertical reciprocation of the knife or knife carrier is secured by connecting its respective ends with cranks on a suitable crank shaft, the pull is all in a downward direction, with the result that the slide block alternately tends to bear on the under side of the guideway and then on the upper side, as the knife cuts through the stock, particularly if the latter, as is usually the case, 25 does not offer a uniform resistance.

The consequent "chattering" of the knife has proven a serious operative difficulty in these machines which it is the object of the 30 present invention to overcome by providing for the application of the power from the crank shaft to the knife in a direction more nearly parallel with the aforesaid guideway, thus eliminating the tendency to chatter. To 35 the accomplishment of the foregoing and related objects, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

55 In said annexed drawing, the single figure

there appearing is a front elevation, partly diagrammatic in character, of a power paper cutting machine embodying my present improvement.

The frame of the machine includes the 60 usual table or bed 1 on which the stock, consisting of a pile of sheets of paper, is placed in order to trim the same. Vertically reciprocably held in suitable standards 2 that rise above said bed is the knife head or stock 3 carrying the knife 4. This stock also carries a resiliently supported presser bar or binder 5 which initially contacts with such stock on the downward stroke of the machine in order to hold the sheets in place pending 70 contact of the knife therewith. Adjacent one of the standards 2 is provided a downwardly and outwardly inclined guideway 6 which slidably receives a block 7 pivotally attached by means of a pin 8 to the knife 75 head or stock 3, as will be readily understood, since this is a familiar construction.

Journaled in the frame below the bed 1 is a power driven crank shaft 9, the cranks 10 on the respective ends thereof being operatively connected with the respective ends of the head 3. At the right-hand end in the Figure as shown the connections comprise a suitable rod 11, the ends of which are attached to the crank and head by universal 80 joints 12 and 13 respectively, and in the prevailing construction the connection at the left-hand end would be the same. In my present improved construction, however, instead of directly connecting the rod 14 at the 85 other end of the machine, i. e. that adjacent the inclined guideway 6, with the corresponding end of the knife head 3, I employ a toggle arrangement as illustrated, consisting of two links 16 and 17 pivotally connected together, said first named link being pivoted at its outer end to a bracket 18 projecting from the end of the machine frame in question, and the other link 17 being pivoted at its outer end to said head at a point 90 a little to the corresponding side of the center thereof. The upper end of the connecting rod 14 is attached to the links 16 and 17 at their point of interconnection through the medium of a suitable universal joint 19, and a universal joint 20 likewise serves to attach the other end of said rod to crank 10.

The mode of operation of my improved machine may now be briefly set forth. With the knife carrier 3 in its upper posi- 110

tion, as illustrated in the drawing, the toggle links 16 and 17 lie with their point of interconnection a trifle below a line connecting their points of pivotal attachment to bracket 18 and said carrier, respectively. Accordingly, when the shaft 9 is rotated to pull downwardly on the connecting rods 11 and 14, simultaneously with the downward pull exerted through said first named rod on the carrier 3, the other rod, pulling on the carrier through link 17, has the path of movement of its upper end constrained by link 16 so as to pull in a direction approximately parallel with slideway 6. There will be a slightly greater component of the pulling force exerted in the upward rather than the downward direction, having regard to the angle of inclination of such guideway, so that the slide 7 will be held against the upper face of the guideway, irrespective of the resistance encountered by the knife in passing through the stock. In other words, there will be no tendency for such knife to chatter, due to the fact that the slide bears at one moment against the lower face of the guide way, and at the next against the upper face. A smooth and uniform cutting stroke is thus secured, insuring the even trimming of the stock, and avoiding the displacement of its component sheets.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a machine of the class described, the combination of a frame including a bed, a knife carrier reciprocable relatively thereto; an inclined guideway; a sliding element en-

gaging said guideway for imparting a transverse movement to said carrier when reciprocated; means for reciprocating said carrier including a crank shaft, connecting rods between said shaft and the respective ends of said carrier, one of said rods being directly attached to the latter, the other of said rods being connected with said carrier through a pair of toggle-links, the outer toggle-link being pivoted to the frame in a horizontal plane intersecting said guideway at approximately its central point, said link being of a length to maintain a light contact of said sliding element against the upper face of the guideway during the full cutting stroke of the knife to prevent chattering thereof. .

2. In a machine of the class described, the combination of a frame including a bed; a knife carrier reciprocable relatively thereto; an inclined guideway; a sliding element engaging said guideway for imparting a transverse movement to said carrier when reciprocated and means for reciprocating said carrier including a crank shaft, connecting rods between said shaft and the respective ends of said carrier, one of said rods being directly attached to the latter, the other of said rods being connected with said carrier through a pair of toggle-links, respectively attached at their outer ends to said carrier and to the machine frame adjacent said guideway but beyond the end of said carrier, said outer toggle-link being of less length than its companion link and the point of interconnection of the rod with the central pivot of the toggle being at all times below a straight line drawn through the outer pivots of said toggle, so that during the cutting stroke of the mechanism a light contact of the sliding element with the upper face of the guideway will be uniformly maintained.

Signed by me, this 7th day of April, 1919.
RALPH S. TYLER.
